DESIGN FOR A MACHINE SEAT

William A. Fleischer, Grand Island, Nebr.

Application September 3, 1946, Serial No. 133,027

Term of patent 3½ years

(Cl. D15—8)

To all whom it may concern:

Be it known that I, William A. Fleischer, a citizen of the United States and a resident of Grand Island, in the county of Hall and State of Nebraska, have invented a new, original, and ornamental Design for a Machine Seat, of which the following is a specification, reference being had to the accompanying drawing, forming part thereof.

Figure 1 is a top plan view; Figure 2 is a front elevational view; Figure 3 is a side elevational view, of a machine seat, showing my new design.

I claim:

The ornamental design for a machine seat, as shown.

WILLIAM A. FLEISCHER.
